UNITED STATES PATENT OFFICE.

HIRAM V. BOWMAN, OF TOLEDO, ILLINOIS.

GAS-ENGINE VALVE.

1,157,077.

Specification of Letters Patent.

Patented Oct. 19, 1915.

Application filed April 25, 1912. Serial No. 693,148.

To all whom it may concern:

Be it known that I, HIRAM V. BOWMAN, a citizen of the United States, residing at Toledo, in the county of Cumberland, State 5 of Illinois, have invented certain new and useful Improvements in Gas-Engine Valves; and I do hereby declare the following to be a full, clear, and exact description of the invention, such as will enable others skilled 10 in the art to which it appertains to make and use the same.

My invention relates to new and useful improvements in rotary valve constructions and more especially to rotary valves for use 15 as intake and outlet valves for internal combustion engines, and the object of my invention is to improve the construction and increase the efficiency of valves of the above nature. And a further object of my invention 20 is to provide a rotary valve which may be employed as both the intake and outlet valve of both cylinders of a two cylinder, four-cycle engine.

With these and other objects in view, my 25 invention will be more fully described, illustrated in the accompanying drawings which show a preferred embodiment of my device and then specifically pointed out in the claim which is attached to and forms 30 a part of this application.

In the drawings, Figure 1 is a fragmentary sectional view of the cylinders of a two cylinder engine, each having a single valve 35 port acting as both an outlet and inlet port, showing my improved valve in operation. Fig. 2 is a transverse section through the line 2—2 of Fig. 1. Fig. 3 is a perspective of the valve, the valve casing being shown in section. Fig. 4 is a perspective of a modified form of my valve adapted for use as 40 either an inlet or an outlet valve. Fig. 5 is a perspective of a somewhat similar form of valve. Fig. 6 is a sectional view of a single cylinder engine showing the valves 45 shown in Figs. 4 and 5 employed as intake and exhaust valves therefor. Fig. 7 is a transverse section on the line 7—7 of Fig. 6.

Referring more specifically to the drawings, in which similar reference numerals 50 designate corresponding parts throughout, 10 and 11 designate the cylinders of a two cylinder, four-cycle engine of the type in which each cylinder has a single port adapted 55 to serve both as an inlet and outlet port. 12 and 13 designate the piston and 14 and 15 the ports respectively of the two cyl-

inders. Positioned between these cylinders and communicating with the ports thereof, is the valve casing of my valve, comprising a vertically extending cylindrical body 60 member 16 open at both ends and provided adjacent its lower end with an inwardly directed annular flange 17. This body member is provided intermediate its length with laterally directed, diametrically disposed 65 chambers 18 and 19 the former of which is terminated by a port 20 registering with the port 14 of the cylinder 10 while the latter is provided with a port 21 registering with the port 15 of the cylinder 11, these 70 chambers communicating throughout their entire extent with the interior of the casing. Closely fitting within this casing and rotatable therein, is my improved valve comprising a cylindrical body member 22 75 which is open at both ends and which is seated by its lower end upon the flange 17 of the valve casing. Brace rods 23 extend transversely across the lower end of the valve body and form a connection for the 80 upper end of the valve stem 24 the free end of which is directed downwardly and terminates in position to be rotated by the crank shaft of the engine through the intercession of any suitable gears. The valve is 85 provided with spaced apart, longitudinally extending ports 25 and 26 the former of which forms the intake port of the valve while the latter forms the outlet port. The valve body is provided longitudinally 90 throughout the greater portion of its length by an axially positioned partition wall 27, one of the ports being positioned upon one side of the wall while the other port is positioned upon the opposite side. The upper 95 end of this wall is provided with a laterally directed extension 28 which closes the upper end of the intake chamber of the valve while the lower end of the wall is provided with an oppositely directed extension 29 which 100 closes the lower end of the outlet chamber of the valve. Communicating with the lower end of the valve casing is the inlet pipe 30 while an exhaust pipe leads from the upper end of the valve casing.

In Figs. 1 and 2 I illustrate the valve in the position occupied when the piston of the cylinder 10 is at the end of its intake stroke while the piston of the cylinder 11 is at the beginning of its exhaust stroke. It will of course be understood that the gearing by means of which the valve is rotated is adapt-

ed to rotate the valve through one complete revolution while the crank shaft revolves twice.

From the foregoing description, taken in connection with the drawings, the operation of my valve will be readily understood.

In the remaining figures I have illustrated a somewhat modified form of valve construction adapted for use as an intake or outlet valve.

The valve shown in Fig. 4 of the drawings, comprises a cylindrical casing 32 open at its upper end, closed at its lower end and provided intermediate its length with a laterally extending chamber 33 having a port 34 adapted to register with the inlet port of the cylinder. Positioned within this valve casing is the valve comprising a hollow cylindrical body member 35, also closed at its lower end and resting upon the bottom of the valve casing and this valve body is provided with a longitudinally extending valve port 36 which, in one position of the valve, registers with the chamber 33 of the valve casing. Extending upwardly and centrally through the bottom of the valve casing and secured to the closed lower end of the valve is the valve stem 37 by means of which the valve is rotated in its casing. In Fig. 5 I have illustrated a slightly modified form of the valve shown in Fig. 4, this valve being especially adapted for use as an exhaust valve. In this form of valve the valve casing 38 is open at its lower end and closed at its upper end as also, is the valve 39 which rests upon an inwardly directed, annular flange 40 formed adjacent the lower end of the valve casing. The valve stem 41 of this valve extends upwardly through the open

lower end of the valve casing and is secured by the transversely extending cross braces 42.

In Figs. 6 and 7 I have illustrated a conventional form of single cylinder gas engine showing the valve shown in Figs. 4 and 5 in operation, the engine being shown at the beginning of its compression stroke.

From the foregoing description it will be apparent that I have provided a simple and efficient form of rotary valve which will serve both as an inlet and an exhaust valve for both cylinders of a two cylinder, four-cycle internal combustion engine.

It will further be apparent that by slight modifications the valve may be adapted to serve as a simple valve for either the intake or exhaust valve of a single cylinder.

It will of course be understood that minor changes in the details of construction may be made if desired without in the slightest degree departing from the spirit of my invention.

What I claim is:—

An engine valve comprising the combination with an open-ended cylindrical casing of an annular shoulder formed on the inner periphery of the casing, a cylindrical hollow valve body rotatable in the casing and seated on the shoulder, a central partition disposed in the valve body and provided at its lower end with a threaded socket and an actuating stem threadedly engaged in the socket.

In testimony whereof, I affix my signature, in presence of two witnesses.

HIRAM V. BOWMAN.
